ABSTRACT OF THE DISCLOSURE

A device comprising a pair of vertically extending slide surfaces in opposed relation movable apart for slidably receiving an elongated, generally pear-shaped, object, or pear, between the upper portions of said surfaces with the main body of said object in slidable engagement with said surfaces at generally diametrically opposite single points only on said body, for downward sliding between said surfaces and for automatic pivotal movement during said movement so the protuberance on said body will swing under the influence of gravity to a downwardly projecting position for dropping in said position from the lower portion of said surfaces.

BACKGROUND OF INVENTION

In the pear canning industry the orienting of pears for coring and peeling has heretofore involved relatively expensive and complicated machinery incorporating rollers, brushes and other elements having high maintenance and inspection expense, and where mechanical peelers are used the pears are manually oriented and fed to the peelers.

In the present invention, the device for orienting and for feeding the pears for subsequent processing, such as either peeling or coring, or both, is more economical to make, operate and maintain, and to more efficiently and accurately orient and feed different sizes of pears irrespective of irregularities in surface contours of such pears, than heretofore. Furthermore, the orienter is readily adapted to be installed on conventional pear peelers and corers substantially without modification of such peelers and corers.

SUMMARY

The present orienting device is one for orienting a pear or pear-shaped object having perpendicularly disposed major and minor axes, and a main body portion at one end of said major axis and a neck portion at the other end of said major axis adjoining each other. The main and body portions are generally of circular cross-sectional contour, and the main body portion is substantially larger than the neck portion. The pear is oriented so that the major axis is substantially vertical with the neck portion directed downwardly.

The method and apparatus are such that the pear is pivotally supported between and against a pair of spaced opposed surfaces at a pair only of single, substantially opposite points at the outer surface of its main body, which points are disposed at substantially the maximum diameter of the body on an axis extending transversely of said major axis for swinging the neck portion to a downwardly extending position under the influence of gravity.

The pear is moved downwardly under the influence of gravity during its pivotal movement, so as to be discharged at the lower end of its path with the neck end projecting downwardly, so that each pear will be uniformly positioned for subsequent processing, such as peeling and coring, or otherwise.

2**BRIEF DESCRIPTION OF DRAWINGS**

In the drawings, FIG. 1 is a side-elevational view of the orienter and feeder in a position with an unoriented pear at the upper end, and a conventional receptacle at the lower end to receive the oriented pear;

FIG. 2 is a side-elevational view of FIG. 1 as seen at a right angle to the view of FIG. 1;

FIG. 3 is a top plan view of the device of FIG. 1 with certain parts of the frame broken away;

FIG. 4 is a horizontal cross-sectional view through the opposed guide plates only at line 4—4 of FIG. 2 when the guide plates are relatively close to each other. The dot-dash line positions indicate the position of the slides when a pear, also indicated in dot-dash lines, is between the guide plates;

FIG. 5 is a detached elevational view of the plate actuating cam in a position between the cam engaging members that are rigid with the plates;

FIG. 6 is a fragmentary elevational view of the pear-engaging surface of one of the pair of plates between which each pear is oriented, such pear being indicated in dot-dash lines in unoriented and oriented position;

FIG. 7 is a side-elevational view similar to that of FIG. 1 showing a modification of the plate actuating means.

FIG. 8 is a greatly reduced fragmentary view similar to FIG. 1 showing a modification of the invention different from FIGS. 1 and 7;

FIG. 9 is a fragmentary reduced size view showing a further modification.

DESCRIPTION OF EMBODIMENT

The orienter and feeder comprises a pair of vertically extending and vertically elongated, opposed guide plates or members 1 that, in turn, are supported for movement toward and away from each other.

In FIGS. 1, 2 the means disclosed for supporting said plates for the aforesaid movement comprises vertically extending arms 2 that are pivotally connected at their lower ends to a horizontally disposed base frame member 3 by pivots 4.

The opposed faces 5 (FIG. 4) of plates 1 are each preferably formed to provide a very shallow channel extending longitudinally of each plate, the bottom of which is shown as being substantially centrally positioned between the side edges of the latter, and concavely rounded so that the main, enlarged body portion of a pear, the latter being generally designated 6 (indicated in dot-dash lines in FIG. 4) will not contact plates 1 at more than one point on each surface 5 when the pear is descending between the plates 1. In FIG. 4 the plates 1 are indicated in dot-dash lines in expanded or spaced relation with the pear 6 between them and in engagement with the faces 5 at the bottoms of the channels.

Hereinafter the pears, wherever indicated in the drawings, whether in full or dot-dash lines, will be generally designated 6, it being understood that in actual practice, only one pear is between the opposed faces at a time, hence where more than one is shown (FIGS. 1, 6), the pear is indicated in different positions during the descent of said pear between said surfaces, or during passage through the device.

Preferably the opposed faces 5 of plates 1 are generally parallel with each other when no pear is between them straight from end-to-end, but the lower portions 7 at the sides of the bottom (FIG. 6) may be relieved to extend slightly away from each other in a downward direction.

Inclined walls 8 at the upper ends of plates 1 extend divergently upwardly relative to each other from said upper ends to receive pears 6 thereon for rolling of said

pears to between the upper ends of said plates for downward movement between the plates when the latter are moved apart. Each of the inclined upper surfaces of the walls 8 may be flat or planar except for a ridge 9 (FIGS. 1, 3) that extends slantingly from a point midway between the upper end of each plate across each wall toward diagonally opposite upper corners of the pair of walls (FIG. 3).

A vertical wall 10, secured to each wall 8 at one of the lateral ends thereof extends horizontally across the lateral end edge of the wall 8 opposite thereto to close the space between the pair of walls 8 at their lateral ends, so that the walls 8 and 10 coact to provide an expansible hopper for each pear that is fed onto the upper inclined surfaces of walls 8.

The ridges 9 insure against a pear entering the channel defined by faces 5 centrally thereof at the upper ends of plates 1, so that when the upper ends of plates 1 move apart to admit the pear to between said ends, its entry will be at one side or the other of the bottom of the channel.

The walls 10 of the expansible hopper will remain closed during movement of the plates and walls 8 toward and away from each other.

A horizontally extending coil spring 13 is connected at its ends to arms 2 at points intermediate their upper and lower ends for yieldably urging plates 1 toward each other at all times.

A projection 17 (FIGS. 2, 3) projecting laterally from the same side of each arm 2 and outwardly relative to plates 1, is rigid with each arm, and a cam 18 is positioned between said projections 17, which cam is rotatable about a horizontal axis, being secured on one end of a shaft 19 that, in turn, is connected with a motor or other suitable source of power 20. Spring 13 yieldably holds the projections, or cam-engaging members 17, against opposite sides of cam 18.

Cam 18 has oppositely outwardly extending corresponding lobes 23 (FIG. 5), each having corresponding arcuately extending cam surfaces 24 facing oppositely outwardly from shaft 19 and extending progressively further from points diametrically opposite to each other adjacent to said shaft.

The cam engaging members 17 engage said cam surfaces substantially at said diametrically opposite points when the plates 1 are at their closest positions relative to each other, and as the cam rotates clockwise (FIGS. 1, 4) plates 1 swing apart to their widest spacing upon the outer end portions of surfaces 24. When the maximum spacing between faces 5 is reached, the lower portions 7 (FIG. 5) of said faces will be spaced apart a greater distance than the maximum diameter of the largest body portion 25 of any pear fed into the hopper at the upper ends of plates 1 so such pear will drop from between said plates 1.

The aforesaid largest body portion 25 is the portion adjoining the stem end portion 26 (FIG. 1) and the maximum diameter of said portion 25 is the diameter transversely of the longitudinal axis of the pear that extends through portion 26.

Below the lower ends of plates 1, a cup assembly generally designated 27 is shown, which assembly may be the same as indicated at 177 in U.S. Patent 3,055,408, issued Sept. 25, 1962, to T. M. Harrer et al., including the actuating means, or as generally designated 6 in U.S. Patent 3,332,559, issued July 25, 1967 to M. W. Loveland. This assembly is part of a pear corer and peeler, of the type described in said patents, in which the pear-receiving cup 28 is adapted to receive a pear having its stem-end portion directed downwardly for manual positioning of a pear therein with the stem end down, after which the pear is moved away from the receiving point and is tilted to a horizontal position for impalement on a spindle of a pear peeler and corer, substantially of the type shown and described in the above-designated Patent No. 75

3,055,408, or in FIG. 4 in U.S. Patent 3,018,179 of Jan. 23, 1962 to B. C. Coons et al. The cup assembly is not part of the present invention, and is indicated merely to show one application of the present invention, it being understood that the present invention is adapted for use wherever orientation of elongated, generally pear-shaped objects is desired. As will later appear, by the present invention, a pear or the like will always be discharged from between the lower ends of plates 1 with the stem end portion pointing downward, irrespective of its position at the upper end of the plates.

Any suitable conventional unit feeder may be employed to feed pears, at predetermined timed intervals, to the upper ends of plates 1 for downward passage between faces 5 of said plates. Only a single pear is fed to each orienting device at a time, although it is obvious that a battery or row of such devices may be employed with each peeler and corer corresponding in number to the number of peeling and coring elements in each machine, each of some of such machines having many such elements for peeling and coring many pears at a time.

At the present time, most mechanical peelers are manually fed, as hereinbefore noted, each pear being manually placed in a transfer cup in oriented position by an operator.

The speed of motor 20 or of any conventional transmission between the motor and the cam shaft 19 may be varied to correspond to the time each pear receiver is positioned below plates 1.

In the modification as shown in FIG. 7, the difference between the device illustrated in FIGS. 1-5 and that of FIG. 7 is in the manner of moving the plates 1, hence the same numbers will be used as in FIGS. 1-4 where the parts are the same. Thus the cam-engaging members 17, cam 18, shaft 19, and motor 20 are omitted.

In FIG. 7 the cup assembly 27 is indicated in dot-dash lines and this view is from the side opposite to that of FIG. 1.

A double-acting cylinder and piston assembly 30 includes a vertically disposed stationary air cylinder 31 having a piston 32 vertically reciprocable therein, which piston has a vertical piston rod 33 vertically slidable in a stationary guide bearing 34 for vertical reciprocable movement, and secured to rod 33 is a generally wedge-shaped element 35 having oppositely outwardly facing cam surfaces 36 extending divergently upwardly. Said surfaces 36 are divergent at a wider angle relative to vertical at their lower end portions than at their upper end portions for a reason that will appear later on.

Said element 35 is supported in a position along one lateral side of the pair of plates 1 and arms 2, each having a roller 37 supported thereon in a position at said one side at points intermediate the upper and lower ends of arms 36, which rollers are equally spaced above pivots 4 and are preferably flanged to receive one of the wedge sides of element 35 between the flanges of each roller, and the cam surfaces 36 of said sides will be against the rollers.

When piston 32 is at the uppermost end of its movement, rollers 37 are at the convergent lower ends of surfaces 37, and upon downward movement of said piston, the element 35 will be moved downwardly and plates 1 will be progressively moved apart for admittance of a pear between the upper ends of said plates. This movement is relatively rapid during the initial downward movement of element 35 but is relatively slow as the upper portions of surfaces 36 engage the rollers. The maximum opening of the plates is the same as described for FIGS. 1-5.

The surfaces 36 of element 35 are on yieldable arms 38 extending divergently upwardly from piston rod 32 and their upper ends may be connected by an adjusting screw of turnbuckle 39 for spacing said surfaces to move plates 1 apart different distances according to the adjustment that is made.

Inasmuch as the movement of cup assembly 6 in the above Patent 3,332,559 is air actuated, it is obvious that the air-actuated assembly 30 of FIG. 7 may readily be applied to the device shown and described in said patent for moving the cup assembly 27.

Referring to the modification shown in FIG. 8, side plates 43 may correspond to side plates 1, with a similar expansible hopper 44 at the upper ends thereof, and sets of parallel rods 45 may be pivotally connected at one of their ends to said plates at points along one of the lateral edges of the latter, while the opposite ends of rods 45 are pivotally connected to a vertically reciprocable rod 46. The rod 46 may be vertically reciprocated by a double acting air cylinder 48 similar to that of assembly 30, or by any other suitable means, said rod 46 being connected with the piston in the cylinder 48.

Plates 43 are respectively on carriages 49 that, in turn, may be supported by rollers 50 on stationary rails 51. Obviously, the carriages may be supported in different manners for horizontal reciprocable movement toward and away from each other.

Upon upward movement of the rod 46 the sides 43 will move apart, and upon upward movement of rod 46 they will move toward each other.

A cup 52, such as in assembly 27 or in any other arrangement, may be positioned below plates 43 to receive each pair that is discharged from the lower end of the space between the plates.

In the modification of FIG. 9, the side plates 54 may have the same contours on their opposed faces as those of FIG. 1, but plates 54 are, in turn, pivotally connected at their lower ends 55 to arms 56 that correspond to arms 2, and in FIG. 9 the arms 56 are adapted to move toward and away from each other in the same manner as arms 2, but the upper end of the plates are yieldably held away from the arms 1 by springs 57. The upper ends of the plates 55 have divergently upwardly extending walls 59 that may have vertical end walls 60 corresponding to end walls 10 and that function in the same manner for the same purpose.

This form of invention may be suitable where a battery of adjacent or adjoining orienters may be desired and where the sizes of pears fed to each orienter may widely vary. The yieldability of the plates 55 independently of arms 57 but under the influence of the pears enables each set of plates to yield differently in those instances where the arms of the battery of orienters are connected for simultaneous actuation at predetermined uniform distances.

In operation, referring to FIG. 1, the slope of walls 8 is sufficient to insure downward sliding of a pear deposited thereon for passage into the space between the upper ends of plates 1 upon said plates moving apart sufficiently to receive such pear, and the ridges 9 will insure the pear entering the space between said plates at one side of the bottom of the vertically extending shallow channel on the opposed faces of the plates. In some instances only one plate need be formed with a channel, but it is essential to the successful orienting operation that the opposed surfaces of the plates be such that the pear will engage said surfaces at two opposite points only. By this structure, the pear is pivotally supported at said points for downward swinging of the neck portion under the influence of gravity.

If the pear were deposited centrally between the sides of the channel, in some instances, where it is positioned with the neck extending vertically upwardly, the pear may not rotate to swing the neck downward, but where it is compelled to move laterally to the center of the channel, it will be unbalanced for downward swinging of the neck portion.

Many pears have surface irregularities that may also tend to prevent swinging of a pear descending between the opposed surfaces, but by relieving the opposed sur-

faces at 7 (FIG. 6) at opposite sides of the bottom of the channel, there can be no resistance to rotation of a pear due to possible contact between the neck portion 26 of the pear and the faces of the plates at opposite sides of the bottom of the channel, a pear will freely rotate about the two opposite points in contact with the bottom of the channel.

The contour of cams 18, 35 and the position of pivots 4 result in a relatively sudden slowing of the rate of descent of a pair from the initial relatively rapid descent, each materially contribute to complete swinging of the neck portion 26 to a downwardly extending position under the momentum developed in the neck portion 26, in such pears as may resist such swinging.

In canneries the pears are usually wet when fed to the peeler and corer, hence they readily slide between the plates, and if desired, said surfaces may be of Teflon or any other anti-friction material.

The rate of movement downward of the pears may be controlled by the rate of movement of the plates 1 away from each other. Normally the interval between movement of the feeding cup 28 from below the orienter to the peeler, is relatively long, inasmuch as each transfer of a pear to the peeler is delayed until a previously positioned pear is peeled. Inasmuch as the present orienter is capable of orienting pears at a far faster rate than a peeler is capable of peeling, one orienter may serve a plurality of peelers.

While I have illustrated and described the invention in detail, I do not wish to limit myself to the precise details shown and described, but desire to avail myself of such variations and modifications as may come within the scope of the appended claims.

I claim:

1. Orienting apparatus for orienting a pear and the like having perpendicularly disposed major and minor axes and a main body portion at one end of said major axis and a neck portion at the other end of said major axis adjoining said main body portion so that said major axis will be vertically extending with said neck portion, said main and said neck portions being generally of circular outline in cross-sectional contour, and said main body being substantially larger than said neck portion, comprising:
  - (a) a pair of vertically extending members having generally opposed vertically extending surfaces,
  - (b) means supporting said members for movement away from each other with said surfaces extending convergently relative to each other in a downward direction during said movement, from a position in which a pear is received between the upper portions of said surfaces in engagement with the latter at opposite points on said body portion, to a position in which such pear continues to move downwardly between said surfaces under the influence of gravity to and past lower end portions of the latter,
  - (c) means connected with said members for so moving the latter apart at a predetermined rate of speed for permitting said downward movement of said pear,
  - (d) said members being of greater width than the maximum length of a pear, and at least one of said opposed surfaces being formed to provide the sides of a vertically elongated channel of concave shape in cross-sectional contour facing the other member for guiding a pear between said members along a vertical path parallel with said channel,
  - (e) means at the upper ends of said members for guiding pears to one side of the upper end of said channel for entering said channel at one side of the center of the latter whereby each pear will center itself relative to the sides of said channel for said downward movement along said vertical path when each pear is between said surfaces and in engagement with both as said members are moved apart for permitting said

downward movement of said pear under the influence of gravity.

2. In apparatus as defined in claim 1;

(f) the surface of said other member that is opposed to said channel being formed to provide the sides of a vertically elongated channel corresponding to the first-mentioned channel, whereby the sides of both channels will cooperate for so centering a pear between said channels and for guiding a pear along said vertical path when so centered.

3. In apparatus as defined in claim 1;

(f) said means at the upper ends of said members for guiding pears to one side of the upper end of said channel comprising a wall extending slantingly upwardly and outwardly from the upper end of one of said members for supporting a pear deposited thereon for sliding or rolling downwardly thereon to between the upper ends of said members and ridge over each member extending slantingly thereacross for deflecting such pear during its movement downward on said wall to said one side of said channel.

4. Orienting apparatus for orienting a pear and the like having perpendicularly disposed major and minor axes and a main body portion at one end of said major axis and a neck portion at the other end of said major axis adjoining said main body portion so that said major axis will be vertically extending with said neck portion movement, said main and said neck portions being generally of circular outline in cross-sectional contour, and said main body being substantially larger than said neck portion, comprising:

(a) a pair of vertically elongated members of corresponding length and of greater width than the maximum length of a pear, said members being in side-by-side relation having spaced, opposed surfaces formed to provide shallow channels of generally concave shape in cross-sectional contour for engaging opposite sides of a pear for centering a pear between said channels and for guiding such pear for downward movement in a vertical path,

(b) means supporting said members for movement away from each other with said channels extending

5
10

convergently relative to each other in a downward direction during such downward movement of a pear therebetween from a position in which a pear is received between the upper ends of said channels in engagement with said surfaces at opposite points on said body portion, to a position in which said pear continues downward movement between said surfaces under the influence of gravity to and past the lower end portions of the latter,

(c) guide means respectively at the upper end of each of said members for guiding a pear to a position between the upper ends of said channels at points offset laterally to one side or the other of the centers of said channels, respectively, for downward and lateral movement of said pear to a position centered between said channels for continued downward movement along a vertical line and discharge from the lower ends of said members when such pear is between said surfaces and in engagement with both as said members move apart for permitting downward movement of said pear.

5. In apparatus as defined in claim 4;

(d) said guide means comprising a pair of pear supports rigid with said members for movement therewith extending slantingly upwardly and outwardly relative to each other with the lower end of each at the upper end of one of said members for supporting pears thereon for sliding, by gravity, over the lower ends of said supports and for discharge of said pears into the space between said upper ends of said members at said points.
